UNITED STATES PATENT OFFICE

99,435

DESIGN FOR AN ASHTRAY

Albert C. Grunwald, River Forest, Ill., assignor to Precision Metal Workers, Chicago, Ill., a corporation of Illinois

Application December 9, 1935, Serial No. 59,957

Term of patent 7 years

To all whom it may concern:

Be it known that I, Albert C. Grunwald, a citizen of the United States, residing at River Forest, in the county of Cook and State of Illinois, have invented a new, original, and ornamental Design for an Ashtray, of which the following is a specificcation, reference being had to the accompanying drawing, forming part thereof.

Figure 1 is an isometric view of an ashtray embodying my new design; and

Figure 2 is a vertical section taken on the line
2—2 of Figure 1 and looking in the direction indicated by the arrows.

I claim:

The ornamental design for an ashtray as shown.
ALBERT C. GRUNWALD.
